UNITED STATES PATENT OFFICE.

WALLACE C. WRIGHT, OF BROOKFIELD, NEW HAMPSHIRE, ASSIGNOR TO HARDING ENGINEERING COMPANY, OF EAST BOSTON, MASSACHUSETTS, A CORPORATION OF MASSACHUSETTS.

METHOD OF SLICKING HIDES.

Application filed March 14, 1927. Serial No. 175,200.

My present invention relates to the manufacture of leather and more particularly to an improved process or method ofslicking hides during the manufacture thereof.

5 In my copending application, Serial No. 175,199, filed March 14, 1927, I have described and claimed an improved method of slicking hides consisting essentially of taking the hides or skins as they issue from the 10 putting out machine, passing the same over a roll for applying adhesive thereto, simultaneously associating therewith a slicking board, passing the same to a slicking machine such as is described and claimed in my 15 copending application, Serial No. 190,749, filed May 12, 1927, and then passing the slicked hide onto a drying compartment or to a place where other operations may be performed thereon. I have found that to 20 obtain the best effects from the slicking process that other operations than that performed by the slicking machine should be performed on the hide or skin, and, further, due to lack of room, means should be devised for permitting the slicking of more 25 than one hide or skin on the slicking board.

In developing this invention, I have devised a method by means of which a plurality of operators may work together as a 30 team for placing and slicking the hides or skins on the slicking board, in addition to that operation performed by the slicking machine and for sending back in a practically continuous stream, the slicking boards for 35 attaching thereto on the other side thereof a second hide or skin. By this method of operation, each slicking board has slicked thereon and on each face, a hide or skin so that a considerable investment is saved on 40 slicking boards and in the cost of drying chambers or ovens.

The object of my invention, therefore, is an improved method of slicking hides or skins.

45 While the method of slicking constituting the present invention may be practiced solely by hand, I have found it more economical and practical to perform certain of the various operations by machines and have, 50 therefore, in the accompanying drawing, illustrated a schematic layout for practicing my improved method.

In the accompanying drawing, the figure

illustrates a plan schematic layout of my invention.

55 Referring to the drawing, 10 designates a putting out machine in which the hide or skin 11 is moved from left to right, or in the direction of the arrow shown and onto a conveyor 12, which passes the hide or skin onto a roll 13, which applies adhesive thereto. After passing over the adhesive roll 13, the hide or skin 11 is moved onto a conveyor 14, or would be moved onto it were it not 60 for the fact that an operator, standing adjacent to the conveyor 14, grasps a slicking card 15 arranged in a pile and places one of the cards under the adhesive roll 13 and onto the conveyor 14, it being understood 65 that the surface speed of the roll 13 is equal to the speed of conveyor 14. The hide or skin 11 is, therefore, placed in position on the slicking board 15 and is carried along by such conveyor and into position under the operating mechanism of a slicking machine 16. This slicking machine is preferably similar to that described and claimed 70 in my copending application, Serial No. 190,749, above referred to.

75 Grouped about the slicking machine 16, 80 and preferably as shown in the drawing, are operator's positions 17, 18 and 19. After the completion of the slicking operation on the hide 11, in position on the slicking board 15, the slicking board 15 with attached hide 11 85 may be passed to either of the operators at positions 17, 18 and 19, where additional operations such as slicking the shoulders, cheeks or butts may be performed. Assume 90 for a moment that the slicking board 15 with attached and slicked hide 11 passes to the operator at position 17, where such operator performs the additional operations necessary, after such operations are completed, the operator at position 17 turns the slicking board 15 downward, on a platform 20, and a workman carries the slicking board 15, or a plurality of slicking boards 15 if such are positioned at 20, and moves along 95 the dash line shown in the direction of the arrow, placing the same eventually in the position from whence it started. If the slicking board 15 with the slicked hide or skin 11 thereon passes from the slicking machine 16 to the operator at position 18, such 100 operator performs the extra operations 105

necessary thereon and turning theslicking board 15 over, places it in the position indicated at 21, where the workman above referred to will in his travel along the dash line, pick up such slicking board or boards and place it or them in the position from whence it started. The same is true likewise if the slicking board 15 with the slicked hide or skin 11 thereon passes to the operator's position indicated at 19, where the extra operations being performed thereon, such slicking board 15 is turned over and placed in the position indicated at 21, where the workman above referred to in his travel along the dash line will pick up the slicking board 15 with attached and slicked hide 11 thereon and place the same in the position from whence it started. Preferably at each position 17, 18 and 19, there are two hand operators in order to expedite the procedure. As the slicking boards 15 are passed onto the conveyor 14 the second time, that is, with one skin 11 already slicked thereon, such slicking board passes to the slicking machine at 16 and from thence to either of the positions 17, 18 and 19. After the extra operations have been performed on the hide or skin 11, the slicking boards 15 now provided with a skin on each face, are placed on tables (not shown), at each operator's position 17, 18 and 19, from whence they are collected periodically by workmen and hung upon hooks, as is usual, and placed in the drying room.

35 By properly routing the slicking boards 15 through the various operators and dispensing with the slow laborious method of applying adhesive to the hide or skin 11 and positioning the hide or skin 11 manually on the slicking boards 15, I speed up production to a great extent and by performing the major operation of the slicking operation by mechanical, as distinguished from manual means, I am enabled to perform a better slicking operation and one which will produce a better finished hide or skin than has heretofore been possible. By grouping the

operators at positions 17, 18 and 19 to perform the extra operations on the hide or skin, and by properly routing the hides 50 or skins on the slicking boards back to the starting point to be sent through the process a second time for the purpose of applying skins to both faces of the slicking boards, I economize greatly on room and expedite to 55 a great extent the method of slicking. The result is a superior product produced at less cost than has heretofore been possible.

Having thus described my invention, what I claim as new is:

1. That improved process of slicking hides or skins which consists in moving slicking boards and hides or skins forward simultaneously while applying adhesive to the skin, assembling each hide or skin and a 65 slicking board in proper position relatively to each other, slicking by mechanical means the major portion of the hides on the slicking boards, and thence passing the partially slicked hides or skin to either of a plurality 70 of operators' positions where additional slicking operations may be performed thereon.

2. That improved process of slicking hides or skins which consists in moving slicking boards and hides or skins forward simultaneously while applying adhesive to the skins, assembling the hides or skins and the slicking boards in proper position relatively to each other, slicking by mechanical 80 means the major portion of the hides on the slicking boards, passing the partially slicked hides to one of a plurality of operators' positions, performing additional slicking operations thereon, turning the slicking boards 85 over to position the hides or skins on the under face thereof, and sending the slicking boards with a hide or skin on the under surface thereof through the slicking process whereby an additional hide or skin is placed 90 on the upper surface of each board.

In testimony whereof, I have signed my name to this specification.

WALLACE C. WRIGHT.
